Attest:

UNITED STATES PATENT OFFICE.

CHARLOTTE M. SHERIDAN, OF CHICAGO, ILLINOIS.

GOLF-SCORE REGISTER.

Application filed September 4, 1925, Serial No. 54,388. Renewed October 1, 1927.

My invention relates to a golf score register and more particularly to an improved device of this type which registers the total score of several of the holes of a course and 5 the score of the individual holes as played.

An object of my invention is to provide a simple and efficient device which may be worn about the wrist and operated substantially in the same manner as a watch, the device 10 consisting of certain peculiarities of construction, novel arrangement and combination of the various parts thereof as will be hereinafter more fully set forth and specifically claimed.

15 A further object of the invention is to provide a device of the above mentioned general character whereby a pair of numeral hands rotate about a dial, one being in the nature of a totalizer which registers the total 20 scores for the game, and the other being provided to register the number of strokes for a given hole. The advantage of using a second hand for this purpose resides in the fact that it provides an indication of the 25 strokes for any one hole as the strokes are made and eliminates inaccuracies in keeping the score due to forgetting, when finishing the play for this hole, the number of strokes that were taken.

30 Other objects and advantages of the invention will be disclosed in the following description and appended claims.

In the accompanying drawings, which 35 serve to illustrate an embodiment of my invention,

Figure 1 is a front elevation of a golf score register embodying my invention showing a portion of the strap which encircles the wrist of the user.

40 Fig. 2 is a side elevation of the device;

Fig. 3 is an enlarged detail view showing the cover removed and a portion of the interior mechanism;

Fig. 4 is a similar view, but omitting a 45 spider member which exerts a spring pressure to hold the toothed wheels of each numeral hand in frictional contact with each other so as to rotate in unison;

Fig. 5 is a cross sectional view taken on 50 line 5-5 of Fig. 4;

Fig. 6 is a perspective view of the toothed

wheel imparting a rotary motion to both numeral hands when registering the score of the several holes of a course and the score 55 for each hole; and

Fig. 7 is a similar view of a toothed wheel adapted to be rotated in a reverse direction to reset the numeral hand registering the score for each individual hole back to zero on the dial.

Referring more particularly to the drawings wherein I have shown a preferred embodiment of my invention, a casing 1 in the form of a watch case is provided with lateral lugs 2 for receiving a strap 3 provided 60 with the usual buckle 4 at one end and apertures at the other which are employed to secure the strap about the wrist of the wearer.

It will be noted in Fig. 1 that a dial 5 70 is provided with any desired number of divisions thereon for registering the total score of several holes of a course and also the score of each individual hole as played.

Actuators in the form of axial movable 75 stems 6 and 7 may be furnished to provide the necessary rotational movement to a pair of hands 8 and 9. From this figure, it will be observed that the small hand 8 may be used to indicate the total score while the 80

large hand 9 may be employed to indicate the number of strokes taken to play a single hole. At the tee of hole number 1, the player 85 operates both stems 6 and 7 to bring both hands 8 and 9 to zero position. It is ap-

parent, of course, that the device will be in this position at the start of any game. By 90 referring to the other figures of the drawing, it will be noted that a pair of concentrically arranged superimposed wheels 10 and 11 are

provided in casing 1. The periphery of 95 each wheel may be furnished with teeth. It is desirable to provide a greater number of teeth on wheel 10 than on wheel 11. A stem 12 is adapted to extend outwardly from

wheel 10 while a pin 13 arranged in the same relation extends outwardly from wheel 11. The interior diameter of hollow stem 12 is slightly larger than the diameter of pin 13 so that when pin 13 is extended in stem 12, 100 each may rotate independently of the other.

It will be noted in Fig. 5 that wheel 11 is

placed below wheel 10 and that the reduced end 14 of pin 13 carries the large numeral hand 9 above dial 5. The reduced end 15 of stem 12 carries the small numeral hand 8. 5 The means provided to carry the wheels 10 and 11 within casing 1 serves also to exert a pressure against these wheels so as to hold them in frictional contact with each other during the registering of the score. A flat 10 plate 16 may be pressed in the casing 1 and provided with an aperture 17 through which the stem 12 passes. This means may be in the form of a spring spider 18 held in position by screws 19 which thread into plate 16. 15 The spider 18 bears against wheel 11 at the point designated 20. This pressure is sufficient to provide a frictional contact which will permit both wheels to move in unison when the larger wheel 10 is actuated. 20 The actuating means may be in the form of a spring element 22 fastened at 23 to a lug 24, struck up from plate 16. By referring to Fig. 3, it will be noted that the left-hand end of spring element 22 is provided 25 with a hump 25 which bears against the actuator stem 6. The free end of spring element 22 at the left-hand side is adapted to engage the teeth of wheel 10 and serve in effect as a pawl for actuating this wheel. 30 The opposite side of spring element 22 is likewise provided with a hump 26 which is engaged by the actuator stem 7. The free end of this side of spring element 22 is also in the form of a pawl 28 which engages the 35 teeth of wheel 11. Pawls 28 and 29 of spring element 22 are so arranged that actuation thereof will provide reverse rotation of wheels 10 and 11. A spring detent 30 is fixed at 31 to a lug 32, also struck up from 40 plate 6 to prevent reverse rotation of wheel 10 when wheel 11 is rotated. The purpose of operating wheel 11 by means of stem 7 is to reset the large hand 9 to zero position as each hole is played, thereby keeping an 45 individual record of the score of each hole. When hand 9 is brought to zero position, a pin 35 extending upwardly from wheel 11 is adapted to engage an elongated depression 36 on the spring spider 18. 50 It will be noted that by merely depressing each stem 6 and 7, it is possible to actuate both hands 8 and 9. The detail construction of these stems has been shown in Fig. 5. The inner end may be provided 55 with a head or enlarged portion 37 so as to prevent the stems from being withdrawn from casing 1. The shank 38 of each stem is adapted to slide within a projection 39 formed on casing 1. It will be understood, 60 of course, that the structural details of this stem may be varied without departing from the scope of the present invention. The operation of my device will now be described. Assuming that the hands are in 65 the starting position, such as has been shown

in Fig. 1, the stem 6 is depressed each time a stroke is made. The inner end of stem 6 presses against the hump 25 and causes the end 29 to successively engage the teeth of wheel 10. The wheel 10 is thereby rotated 70 to cause a step by step rotation of both hands 8 and 9. As soon as the first hole has been played, the stem 7 is then depressed so as to bring the large hand 9 back to zero. Depression of stem 7 engages hump 26 to cause 75 end 28 to rotate wheel 11. This rotation is, of course, in a reverse direction with reference to the rotation of wheel 10. The frictional contact which existed when both hands were rotated by the wheel 10 is now 80 broken to permit this smaller wheel 11 to rotate independently of wheel 10. The detent 30 locks wheel 10 against reverse rotation. It will thus be observed from the above description that a novel form of golf 85 register is provided which will accurately register the number of strokes of all the holes of a single course and at the same time accurately register the number of strokes 90 played for a single hole. 90

It will be apparent that various structural details may be varied and that various modifications may be made without departing from the scope of my invention.

I claim:

1. A golf score register having a pair of independent numeral hands for registering the total score for the several holes of a course and the score for each individual hole, an operator for each hand, a pair of superimposed rotatably mounted toothed disks connected to said hands, resilient spring means operated by the actuation of said operators to rotate said disks to cause a step by step rotation of said numeral hands, frictional means for placing the disk of each numeral hand in cooperation with the other to move said numeral hands in unison by one of the operators in registering the score of the several holes and of the individual holes, and detent means extending inwardly to engage a projection on one of said disks whereby to serve as a stop when said other operator resets the number hand registering the score of individual holes 105 back to zero. 110

2. A golf score register having a pair of independent numeral hands for registering the total score for the several holes of a course and the score for each individual hole, an operator for each hand, concentrically arranged superimposed rotatable wheels connected to said hands, an integral spring member having its free ends comprising pawl members operated by the actuation of said operators for engaging teeth on the periphery of said wheels to cause a step by step rotation of said numeral hands, said pawl members being resiliently mounted to return said operators to normal position, 125 130

means for holding said wheels frictionally and means for locking the other wheel interlocked whereby one of said operators will move both numeral hands in registering the total score of the several holes and of each individual hole, the other operator serving to reverse the rotation of one of said wheels to reset one of said numeral hands, and means for locking the other wheel against reverse rotation to overcome said frictional interlock. 16
In witness whereof, I hereunto subscribe my name this 31st day of August, A. D., 1925.

CHARLOTTE M. SHERIDAN.
